UNITED STATES PATENT OFFICE.

HOWARD N. LINES, OF SABETHA, KANSAS.

DISPLAY-CASE.

1,078,447.

Specification of Letters Patent. Patented Nov. 11, 1913.

Application filed August 3, 1912. Serial No. 713,097.

To all whom it may concern:

Be it known that I, HOWARD N. LINES, a citizen of the United States, and a resident of Sabetha, in the county of Nemaha, and State of Kansas, have invented a new and Improved Display-Case, of which the following is a full, clear, and exact description.

My invention relates to a display case comprising a box or inclosure, and a tray 10 contained within the box and adapted to receive the articles to be displayed.

The invention is more particularly intended for seeds in small packages, but is capable of use for any small articles to be 15 exhibited.

It is an object of my invention to provide a display case in which the opening of the cover will automatically lift the tray to a position to effectively display the goods; and 20 in which the closing of the cover will automatically lower the tray and inclose the same.

For the purpose of carrying out the objects of my invention, a novel means of supporting the tray and connecting it with the case and its cover, is provided, as will be hereinafter more particularly explained.

Reference is to be had to the accompanying drawings forming a part of this specification, in which similar characters of reference indicate corresponding parts in all the views.

Figure 1 is a perspective view of a display case embodying my invention, showing the 35 same in open position; Fig. 2 is a vertical section showing the case closed; Fig. 3 is a fragmentary sectional elevation given to show the manner of connecting the forward end of the tray with the body of the case, and guiding the movement of the tray at 40 said forward end; and Fig. 4 is a fragmentary cross sectional view on a larger scale showing the supporting and guiding means for the front end of the tray.

In constructing a case constituting a practical embodiment of my invention in the form illustrated, a suitable case 10 is formed, preferably rectangular, and provided with a cover 11 hinged to the case at the rear end, 45 as at 12. Within the case a separate tray 13 is arranged, and the forward end of said tray has guided sliding movement on the body 10 of the display case. In the form shown, there are provided on the inner face 50 of each side of the case 10 inclined grooves 14, which may be produced directly in the

material of the case, as in the arrangement shown. The grooves incline upwardly and rearwardly from a point adjacent to the front side of the case and are adapted to receive trunnions or studs 15 provided on the outer sides of the tray 13. In connection with the grooving of the case as at 14, desirably a wear iron or strip 16 is employed, secured to the inner face of each side of the case, the strip being disposed at the said groove 14, following the direction thereof. The said strip presents an upper edge 17 flush with the bottom of the groove 14, and said groove and strip at the upper inner end thereof, each have a drop, thereby producing a recess 18, in which the stud 15 will be received when the front end of the tray reaches the upper end of its movement. In the preferred form, the strip 16 has a return 75 member 16^a spaced from the edge 17 and flush with the upper edge of the groove 14, so that said return member overhangs the upper end of the groove and forms a wear plate against which the stud 15 will contact 80 and be guided in the downward movement of the tray.

The connection between the cover 11 and the tray 13 is established by means of a link 19, the upper end of which is slotted, as at 20, said slot receiving the shank of a stud 21 carried by the cover 11, it being understood that a link and stud are provided at each side of the case. The lower end of each link 19 is pivoted, as at 22, to a lever 23 at a point between the ends of said lever, the lower or rear end of the lever being fulcrumed as at 24 to the side of the case 10, as clearly shown in Fig. 2. The forward or front end of the lever 23 is pivotally 95 connected with the tray 13, the connection advantageously being effected by a stud 25 on the side of the tray, and a slot 26 in the end of the lever 23, said slot 26 preferably being undercut, as at 27, at one side. The arrangement is such that the tray may be disconnected from the lever 23 when desired. By the arrangement shown, it will be observed that when the cover 11 is raised it has an initial movement independently of the tray 13, and said cover and link will move relatively to each other, the link simply swinging with the pivot 22 as a center; when, however, the stud 21 carried by the cover reaches the upper or outer end of the slot 20, the link now will be lifted bodily while 105 swinging on its pivot 22, the result of which 110

is that the lever 23 will be raised and rocked on its fulcrum 24, whereby the outer end of the lever 23 will engage the stud 25 on the side of the tray, said stud being at a point 5 between the front and rear ends of the tray, whereby the tray will have two movements, the one an upward movement with the fulcrum 24 as a center, and the other a bodily sliding movement as the said studs 15 travel 10 in the guideways provided by the groove 14 and elements 16. The tray will thus be raised to an inclined position, and rearward of the front end of the display case.

For the effective display of the articles, 15 the tray is divided longitudinally by transverse partitions 30, the bottoms 31 of which are approximately at right angles to the said partitions. The several divisions of the tray produced by the partitions 30 are 20 each divided by inclined longitudinal partitions 32 which provide intermediate pockets for the reception of seed packages or other small articles. The arrangement of the partitions 30 and the bottoms 31 25 thereof, is such that as the tray is raised upon the opening of the cover, and rocked in a forward direction, it will move through an angle of forty-five degrees to bring the bottoms 31 of the trays to approximately

the horizontal position, so that seed packages, for instance, will be approximately vertical. 30

Having thus described my invention, I claim as new and desire to secure by Letters Patent: 35

A display case, comprising a body, a hinged cover thereon, and a separate tray, links having at one end a slot and pin connection with the said cover, levers pivoted between their ends to the opposite ends of 40 said links, the said levers being pivoted at one end to the body, the opposite ends of the levers having slots extending through the extreme ends thereof, and pins extending through said slots into the tray, the 45 body having guide slots at the forward end inclining upwardly and rearwardly, and laterally projecting pins on the front end of the tray, near the bottom, the pins being movable in the said guide slots. 50

In testimony whereof, I have signed my name to this specification in the presence of two subscribing witnesses.

HOWARD N. LINES.
